(57) **CLAIM**

The ornamental design for a mouse, as shown and described.

DESCRIPTION

FIG. 1 is a front perspective view of a mouse showing our new design;

FIG. 2 is a top view thereof;

FIG. 3 is a right side view thereof;

FIG. 4 is a left side view thereof;

FIG. 5 is a front side view thereof;

FIG. 6 is a rear view thereof;

FIG. 7 is a bottom view thereof;

FIG. 8 is a front perspective view of an alternative embodiment of a mouse showing our new design;

FIG. 9 is a top view thereof;

FIG. 10 is a right side view thereof;

FIG. 11 is a left side view thereof;

FIG. 12 is a front side view thereof;

FIG. 13 is a rear view thereof; and,

FIG. 14 is a bottom view thereof.

The broken line showing of the various unshaded elements of the mouse in FIGS. 1-7 and 10-14 represents unclaimed subject matter and forms no part of the claimed design.
